(57) **CLAIM**

The ornamental design for a three-compartment container, as shown and described.

DESCRIPTION

FIG. 1 is a top plan view of a three-compartment container according to our new design;

FIG. 2 is a front elevational view thereof;

FIG. 3 is an enlarged scale left-side elevational view thereof;

FIG. 4 is an enlarged scale right-side elevational view thereof;

FIG. 5 is a rear elevational view thereof;

FIG. 6 is a bottom plan view thereof;

FIG. 7 is a perspective view thereof;

FIG. 8 is a perspective view thereof in a partially opened condition; and,

FIG. 9 is a plan view of the interior of the three-compartment container in a fully opened condition.
